United States Patent Office.

JOHN HUGHES, OF NEWARK, NEW JERSEY.

Letters Patent No. 74,691, dated February 18, 1868.

IMPROVEMENT IN HARNESS-PADS.

The Schedule referred to in these Letters Patent and making part of the same.

TO ALL WHOM IT MAY CONCERN:

Be it known that I, JOHN HUGHES, of Newark, in the county of Essex, and State of New Jersey, have invented a new and improved Harness-Pad; and I do hereby declare that the following is a full and exact description of the same, reference being had to the accompanying drawings, and to the letters of reference marked thereon.

To the edges of an iron frame, A, made the width of the pad-top, I secure strips, B B, of leather, or something equivalent, for the purpose of nailing or by other process of fastening the bottom, C, of the pad to the frame. These strips are let into the frame, (see Figures 3 and 4,) or they may not be, as shall be preferred. The frame also receives the adjustable nut D, made to move in the slots E E, into which nut the terret is screwed. In the frame are also the holes V V, for fastening in the tufts.

To the lower end of the frame is fastened a piece, F, of leather or other flexible material, forming a part of the frame for the pad, which, being flexible, accommodates itself to the sides of the horse. In the upper end of this piece is a nut, G, which may also be made adjustable, to receive a screw for holding the pad together.

The frame, at the centre, has a socket or recess from the bottom, to receive a nut, H, for the hook I, thus bringing the nut smooth with the lower surface of the frame, (see Figure 2.) The hook, when screwed in its place, is prevented from turning or getting loose by means of the braces K K, or other similar devices, which are placed in a recess, T, in the frame. In fig. 2 but one brace is seen, on the left. The right shows one edge of the strip B. The upper end of the brace, being rounded off on the lower side, allows it to be put in or taken out by raising the lower end. It rests under the croup-loop L, on which the hook rests when in its position. The upper end of the brace turns up inside of a slot, M, in the croup-loop, and comes against the square side of the shank of the hook, and keeps it from turning.

The binding, N, of the pad is stitched on to the bottom, C, at O, (see figs. 3 and 4,) before the pad is put together. There is a form, P, over which the binding is folded, better shown in fig. 4, where the section is enlarged for the clearer illustration of the parts.

The edges of the bottom, C, are turned over on to the strips B B, and, with the lower edge of the form, are secured to the strips, it may be, by stitching, but ordinarily by nails or tacks S, which, passing through the strip, are clinched on the under side, by coming in contact with the frame. R is the upper strap of the pad, lying between the binding on either side, called the pad-top.

This pad is a great saving of stock and time, and, consequently, of expense, and is very simple of construction, so that ordinary workmen can put it together. In the old styles, such is the perplexity that but few can make them.

What I claim as my invention, and desire to secure by Letters Patent, is—

1. In combination with the iron frame A, the socket for the nut H, the strips B B, and flexible piece F, constructed as herein described, and for the purpose specified.
2. The braces K K, or their equivalents, for the purpose specified.
3. The binding N, stitched to the bottom, C, before it is put to the frame A, and the form P in the binding, and the mode of securing the bottom and form to the frame.
4. The frame A, with the slots E E and grooves for the strips B B, and holes V V, in the manner and for the purposes specified.
